UNITED STATES PATENT OFFICE

2,505,673

SIGN CONSTRUCTION

James A. Howenstine, Lima, Ohio, assignor to
Neon Products, Inc., Lima, Ohio, a corporation
of Ohio

Application April 26, 1949, Serial No. 89,743

4 Claims. (Cl. 40—125)

1

This invention relates to a sign structure and more particularly relates to a hollow illuminated sign structure having an interior chamber for lighting fixtures and the like.

An object of this invention is to provide a hollow illuminated sign structure in which access can readily be had to the interior for servicing lighting fixtures.

A further object of this invention is to provide a sign structure having a hollow convex or outwardly facing shell, the entire face of which may be illuminated.

A further object of this invention is to provide sign structures that can readily and economically be constructed in large quantities from thermoplastic material.

A further object of this invention is to provide a sign structure having a pair of symmetrical hollow convex faces which may be fully illuminated.

A further object of this invention is to provide an illuminated sign structure of generally rectangular shape which includes a hollow translucent panel having an outwardly extending peripheral flange and a retainer or supporting body portion having a peripheral slot formed from a pair of spaced flanges adapted to fit about and engage the flange of the panel, one of the flanges of the retainer being sectional and a part thereof being removable to permit the panel to be slid lengthwise of the slots to permit access to lighting fixtures mounted behind the panel.

The above and other objects and features will in part be obvious and will in part be apparent from the following detailed description and the drawing, in which:

Figure 1 is a view in side elevation, partly broke away and in section, showing a sign structure constructed in accordance with an embodiment of this invention;

Fig. 2 is a view in section taken along a line II—II in Fig. 1;

Fig. 3 is an enlarged view in section taken along a line III—III in Fig. 1; and

Fig. 4 is a perspective view showing a reinforcing corner piece of the illuminated sign.

In the following detailed description and the drawing, like reference characters indicate like parts.

In Figs. 1 and 2, a sign structure is shown which includes a pair of hollow bowl shaped panels 10 of translucent material held in spaced parallel relation by a supporting framework indicated generally at 12. Each panel may be formed of transparent material, such as a methyl methacrylate resin or the like, having a coating of 55

2

translucent paint bearing appropriate sign indicia, on the inner face thereof. Appropriate indicia may be painted on the inner faces of the panels either in translucent or relatively opaque paint. Each panel 10 is provided with an integral outwardly extending peripheral flange 13 which is engaged by a sectionalized marginal angle-shaped retainer 17. Each panel may be given its coating of paint when in the shape shown in the drawings, or paint may be applied to a flat panel which panel thereafter is formed to the shape shown. The panels may be formed in the manner described in greater detail in the copending application of Samuel Kamin, Serial No. 102,403, filed June 30, 1949.

As shown in Fig. 1 the sign panels 10 may be of substantially rectangular shape, and the framework 12 may be of hollow or annular shape and substantially the same size and shape in cross-section as the flange of each panel 10. The framework 12 is made from a band or strip of metal 14 shaped to form a rectangle having inwardly projecting peripheral flanges 16. The angle shaped retainers 17 are attached to the band 14 adjacent the peripheral flanges 16, one flange 18 of each retainer element being attached to the back of the band 14 while the other flange 19 extends parallel to and spaced from one of the flanges 16 to form slots 20 between flanges 16 and 19. As shown in Fig. 2, the peripheral flange of each panel 10 fits into a slot 20.

Each of the angle-shaped retainers 17 may be formed of separable sections 21 and 22 as shown in Fig. 1, and each section 21 may be of generally U-shaped designed to embrace the end of a sign panel 10. Sections 21 may be held in place by screws 23. When the screws 23 are removed, the U-shaped sections 21 can be removed from the sign and either or both of panels 10 may be slid lengthwise of the slots to give access to the interior of the hollow sign structure, the sections 22 forming rails in which the panels can be slid.

The framework 12 may be reinforced by cross braces 24 welded to opposite sides of each corner of the retaining framework 12. Each cross brace may be formed from a metal strip and, as shown in Fig. 4, includes a central portion 25 and angularly bent tips 25' which may be welded to the backing band 14. A pair of tie rods 26 may extend diagonally across the interior of the sign structure being welded or otherwise firmly attached to the cross braces 24 and to each other.

The sign structure may be supported by support arms 27 which are secured to a wall 28. As

shown in Figs. 1 and 3, the support members 21 are attached to upper and lower sides of the retainer 12 by appropriate bolts 29.

As will be understood, appropriate lighting fixtures, not shown, may be located in the hollow interior of the sign structure, and power leads for the fixtures may be threaded along the support bar and may enter the framework through any suitable aperture provided therein.

The structure shown is simple and economical to manufacture yet provides a pair of convex or relief panels which may be illuminated throughout their entire areas.

The embodiment of the invention described above and illustrated in the drawing is subject to modification in structural details without departing from the spirit and scope of the appended claims.

Having described my invention, what I claim as novel and desire to secure by Letters Patent is:

1. A sign structure which comprises a hollow substantially rectangular body portion having an open side, an inwardly directed peripheral flange about the open side, an elongated sectional angle-shaped retainer, one flange of said retainer being attached to the body portion, the other flange of said retainer being parallel to and spaced from the flange of the body portion to form a peripheral inwardly directed slot about the open side of the body portion, and a translucent panel of dish shape having an outwardly extending peripheral flange adapted to fit in the slot, said retainer including a removable U-shaped portion about an end of the body portion, said panel being slideable lengthwise of said body portion when the U-shaped portion is removed to permit access to the interior of the body portion.

2. A sign structure which comprises a hollow substantially rectangular body portion having open sides, a pair of inwardly directed spaced peripheral flanges on said body portion, there being one flange adjacent the edge of each open side of the body portion, a pair of elongated angle-shaped retainers, there being one retainer on each side of the body portion, one flange of each retainer being attached to the body portion, the other flange of each retainer being parallel to and spaced from one of the flanges of the body portion, the flanges forming a pair of peripheral inwardly directed slots about the open sides of the body portion, and a pair of translucent panels of dish shape, each panel having an outwardly extending peripheral flange adapted to fit in one of said slots, at least one of said retainers including a removable U-shaped portion about an end of the body portion, one of the panels being slideable lengthwise of the body portion when the U-shaped portion is removed to permit access to the interior of the body portion.

3. A sign structure which comprises a hollow substantially rectangular body portion having

open sides, a pair of inwardly directed spaced peripheral flanges on said body portion, there being one flange adjacent the edge of each open side of the body portion, four braces attached to said body portion, one of said braces being attached to each corner of the body portion, a pair of tension members attached to said braces, each tension member being attached to and extending between the braces at opposite corners of the body portion to reinforce the body portion, a pair of elongated angle-shaped retainers, there being one retainer on each side of the body portion, one flange of each retainer being attached to the body portion, the other flange of each retainer being parallel to and spaced from one of the flanges of the body portion, the flanges forming a pair of peripheral inwardly directed slots about the open sides of the body portion, a pair of translucent panels of dish shape, each panel having an outwardly extending peripheral flange adapted to fit in one of said slots, at least one of said retainers including a removable U-shaped portion about an end of the body portion, one of the panels being slideable lengthwise of the body portion when the U-shaped portion is removed to permit access to the interior of the body portion.

4. A sign structure which comprises a hollow substantially rectangular body portion having open sides, a pair of inwardly directed spaced peripheral flanges on said body portion, there being one flange adjacent the edge of each open side of the body portion, four braces attached to said body portion, one of said braces being attached to each corner of the body portion, a pair of tension members attached to said braces, each tension member being attached to and extending between the braces at opposite corners of the body portion to reinforce the body portion, a pair of elongated angle shaped retainers, there being one retainer on each side of the body portion, one flange of each retainer being attached to the body portion, the other flange of each retainer being parallel to and spaced from one of the flanges of the body portion, the flanges forming a pair of peripheral inwardly directed slots about the open sides of the body portion, a pair of translucent panels of dish shape, each panel having an outwardly extending peripheral flange adapted to fit in one of said slots, at least one of said retainers including a removable U-shaped portion about an end of the body portion, one of the panels being slideable lengthwise of the body portion when the U-shaped portion is removed to permit access to the interior of the body portion and means attached to the body portion for suspending the body portion and panels with the panels substantially vertical.

JAMES A. HOWENSTINE.
